SCAFFOLD

Robert W. Hyre, Chattanooga, Tenn.

Application November 28, 1956, Serial No. 624,806

4 Claims. (Cl. 248—354)

This invention relates to scaffolds and more particularly to a scaffold which is adapted for many types of use.

One object of this invention is to provide a scaffold having multiple adjustments for elevation to various heights.

Another object of this invention is to provide like scaffold end frames which may be stacked one upon another to various heights without the use of an internal coupling pin.

Another object of this invention is to provide a light portable scaffold of exceptional strength, and with a minimum of substructure.

Another object of this invention is to provide a scaffold which will maintain a platform in horizontal position regardless of the unevenness of the surface which supports the scaffold.

A further object of this invention is to provide scaffolds which may be assembled in such a manner as to adequately and completely support the concrete forms for a monolithic slab and beams.

Another object of this invention is to provide a scaffold assembly which is adapted to support concrete form work which overhangs the scaffold supports.

Another object of this invention is to provide a scaffold which may be adapted for the low elevation work of brick masons as well as the high and overhead work of carpenters, painters and plasterers.

Another object of this invention is to provide a scaffold beneath which there is ample room for the passage of persons and vehicles.

A further object of this invention is to provide a scaffold frame having attachments which will permit the support of platforms and structural members at varying elevations.

A further object of this invention is to provide a scaffold constructed of tubular frame work having novel means for stabilizing structural members having flat surfaces supported by the tubular portions of the scaffold.

Another object of this invention is to provide a scaffold having vertically telescoping support columns.

A further object of this invention is to provide means for stabilizing the telescoping extensions within telescoping scaffold support columns.

Further objects and advantages of the invention will be apparent from the following description taken in conjunction with the drawings, wherein:

Fig. 1 is a front elevation of the invention;

Fig. 2 is a front elevation of the invention supporting a monolithic concrete slab and overhanging beam;

Fig. 3 is a section taken along the lines 3—3 of Fig. 1;

Fig. 4 is a vertical section taken along the lines 4—4 of Fig. 1, with the beam in phantom;

Fig. 5 is a side elevation of the beam hanger of Fig. 4 in an alternate position;

Fig. 6 is a section taken along the lines 6—6 of Fig. 5;

Fig. 7 is a section taken along the lines 7—7 of Fig. 1; and

Fig. 8 is a top plan view of the tie band.

2

Referring now to the drawings in more detail, a scaffold end frame 10 is constructed of truss 11, preferably of the open-web type having a horizontal upper tubular member 12 and a lower tubular member 13. A zig-zag rod 14 extends substantially the length of the truss 11 and alternately abuts the tubular members 12 and 13 at spaced intervals. Supporting each end of the truss 11 are vertical tubular columns 15. Additional truss members 16 depend from the end portions of truss 11 and 15 are connected to columns 15, to not only lend added rigidity to the scaffold frame 10, but also to afford ample space to permit the passage of persons and vehicles beneath the truss 11. One or more horizontal bars 17 may be included in the truss members 16 for added rigidity, to provide ladders for access to the top of the scaffold, or to support platforms such as 18.

Each column 15 is provided with a set of vertically aligned, equally spaced apertures 19. In horizontal alignment with and diametrically opposed to the apertures 19, 20 are a second set of apertures 20 (Fig. 5).

Adapted to telescope within either end of the columns 15 are tubular extensions 21, having a set of vertically aligned apertures 22 of the same spacing as and adapted to mate with the column apertures 19. Diametrically opposed to the extension apertures 22 are a second set of apertures, not shown, adapted to mate with column apertures 20. To vary the effective length of a column 15, an extension 21 may be telescoped within either or both ends of the column until the column apertures 19 and 20 mate with the extension apertures 22. The column and extension are then locked together by means of a pin 24 inserted into mating apertures.

As illustrated in Fig. 1, the extensions 21 may be telescoped within the bottom of the columns 15 to provide vertically adjustable footings for the scaffold frame 10. The frame may be elevated in increments equal to the spacing between the apertures 19. A preferred spacing of about four inches has proved to be very satisfactory in actual practice. After the column 15 and extension 21 are locked together by pin 24, they may be stabilized against lateral movement by a stabilizer thumb screw 25, as illustrated in Figs. 1 and 7.

When the top of the column 15 is employed as a load bearing support, the telescoping extension 21 may be inserted into the top of the column 15 to provide a vertically adjustable head in the same manner as the extension is used for an adjustable footing.

Inserted in the outer ends of the extensions 21 are leveling screws 26. Fixed to the free ends of the leveling screws are bearing members such as a footing 27 or a T-head 28. Threadedly engaged to the leveling screw 26 for rotation is a handle 29, which also bears against the end of the extension 21. By rotating the handle 29, very fine adjustments in the effective length of the column 15 may be obtained. For example, when the T-head 28 engaging a purlin 30 is elevated to within two inches of its desired height to support a joist 31 by means of the vertical adjustment of the telescoping extension 21, the handle 29 is rotated until the leveling screw 26 urges the T-head 28 and purlin 30 upward the necessary two inches. The same type of manipulation at the bottom of the columns provides for fine elevational adjustments of the scaffold frame 10. The tubular member 12 of the truss 11 may be maintained horizontal when the columns 15 are supported on an uneven surface by individual adjustment of the extensions 21 and leveling screws 26 for each column 15.

As illustrated in the right-hand column 15 of Fig. 1, an extension 21' is used as a footing without a leveling screw 26.

As illustrated in Fig. 2, the scaffold end frames 10 may be vertically stacked by inserting the top of a column 15

of one end frame into a collar 32 fixed to the bottom of the column 15 of a second frame. The bottom of the collar is preferably chamfered to facilitate entry of the top of the lower column.

Illustrated in Figs. 1 and 3 is a bracket 33 wedged between the upper and lower tubular members 12 and 13 of the truss 11, for stabilizing a ledger or sill 34, supported by the upper tubular member 12. The ledger 34 acts as a bearing for the joined ends of beams, joists or purllins 35, which extend transverse to and are supported by the end frames 10. The bracket 33 comprises a vertically disposed plate 36 provided with a notch 37 at the top thereof for engaging the upper tubular member 12 and a notch 38 in the lower portion of the plate for engaging the lower tubular member 13. Recesses 39 are provided in the notches 37 and 38 to fit the rod 14. Flanges 40 extend from the top of and normal to the plate 36 to provide a platform tangent to the upper edge of the tubular member 12 for supporting the ledger 34. The flanges 40 may be provided with securing means such as nails 41, for attaching the bracket 33 to the ledger 34. The bracket 33 is so constructed that it may be easily inserted in the truss member 11 without danger of being displaced. The only securing means required are the nails 41 for attachment to the ledger 34.

The versatility of the scaffold end frame 10 is increased by attachment of a beam hanger 42 to any of the columns 15 as illustrated in Figs. 1, 2, 4, 5 and 6. The beam hanger 42 comprises a U-shaped bracket 43 for supporting the end of a beam 44. The hanger 42 is provided with a column clamp 45 having depending arms 46 adjustably attached to the bracket 43. The arms 46 contain apertures 47 adapted to mate with apertures 48 in the bracket 43. Column clamp 45 comprises a U-shaped member having in the web portion 49 an aperture 50 to mate with a pair of aligned column apertures 19 and 20. The flange portions 51 of the clamp 45 contain a pair of aligned apertures 52 for mating with the column apertures 19 and 20, and are provided with another pair of apertures 53 adapted to receive a bolt 54 bounding the outside of the column 15 engaged by the clamp 45.

When the beam hanger 42 is attached to a column 15, as indicated in Fig. 1, with one of the flanges 51 supported by a horizontal structural member such as 17, the bolt 54 may be inserted through the apertures 53 outside the column 15. If the flange 51 is not supported by a horizontal structural member, as in Fig. 2, the bolt 54 is inserted through the web aperture 50 and column apertures 19 and 20.

When the beam hanger 42 is rotated through 90° or the column 15 is provided with aligned apertures at right angles to apertures 19 and 20, the bolt 54 is inserted through the flange apertures 52 and the column apertures, as indicated in Figs. 5 and 6.

After the clamp 45 is secured to the column 15, the beam 44 may be vertically adjusted by raising or lowering the bracket 43 relative to the arms 46 and inserting pins or bolts 55 in mating apertures 47 and 48. As illustrated in the lower beam hanger 42 of Fig. 2, finer adjustments may be provided by a screw 56 extending vertically through the bottom of the bracket 43 and bearing against the bottom of the supported member, such as strut 57.

One use of the beam hangers 42 is disclosed in Fig. 1, in which the beam 44 is supported at each end by a pair of beam hangers hung from adjacent columns 15 of two scaffold end frames 10 spaced apart from each other. This beam 44, in turn, supports the forms for a concrete beam 58.

Another use of the beam hangers is disclosed in Fig. 2 in which an overhanging concrete beam form 59 is supported by a beam 60 and strut 57, the ends of which rest in beam hangers 42 supported from the same column 15.

For supporting structures, such as concrete beam forms, which run parallel to the plane of the end frames 10, the beam hangers 42 may be hung at right angles to their

positions shown in Figs. 1 and 2 in the manner disclosed in Figs. 5 and 6.

The sets of spaced apertures 19 and 20 provide means for attaching a beam hanger 42 at various positions along the entire length of the column 15. The extension apertures 22 have the same spacing as the column apertures 19 and 20 so that when the extension 21 is locked in the column 15, all the column apertures will remain unobstructed to receive the beam hanger bolt 54.

Fig. 1 discloses a preferred means of containing the beam sides 61 during the setting of the concrete beam 58. A tie band 62 having apertures 63 spaced the length thereof is disposed transversely beneath the beam bottom 64. Wedges 65 are inserted in the apertures 63 on opposite sides of the beam 58 to hold kickers 66 against the beam sides 61, thus compressing both beam sides against the beam bottom.

Scaffolding fabricated according to this invention has proved itself adaptable to more varying situations, particularly in concrete form work, than other types of scaffold units. This scaffolding has combined into a compact unit many features heretofore found in independent and cumbersome scaffold units.

This scaffolding is provided with vertical adjustments from fractions of an inch to several hundred feet, by provision of leveling screws, telescoping extensions and the stacking of one scaffold end frame upon another.

The scaffold end frames 10 are constructed to straddle sidewalks, passageways, permanent obstacles, outdoors or indoors, such as walls, steps or church pews, without sacrifice of strength in the scaffold structure. The scaffold end frames can be arranged with their various attachments to completely support a monolithic concrete slab and beam structure, including beams running at right angles to each other, and beams which overhang the scaffold foundations.

The truss members 16 provided with horizontal bars 17 provide ladders to enable carpenters, painters or plasterers to ascend to a platform supported by the truss 11. The horizontal bars 17 may also support platforms 18 for the low elevation work of skilled laborers, such as brick masons, and vehicles containing brick or mortar may be transported to the site of construction beneath the truss 11 and between the truss members 16.

In addition to its many uses, the scaffold according to this invention is extremely strong, light, portable and occupies a minimum of space.

It will be apparent to those skilled in the art that various changes may be made in the invention, without departing from the spirit and scope thereof, and therefore the invention is not limited by that which is shown in the drawings and described in specification, but only as indicated in the appended claims.

What is claimed is:

1. In scaffolding for supporting concrete slab and beam forms, the combination of: a scaffolding end-frame comprising an integral, inverted U-shaped structure made up of spaced, vertically disposed, tubular leg members, a horizontal load-supporting member extending therebetween at a level below but adjacent that of the upper ends of said leg members and means for trussing said leg members, upper and lower leg extensions telescopically related to upper and lower ends respectively of said leg members, said leg members and leg extensions being each provided with a plurality of cross-pin receiving holes spaced at predetermined equal distances from one another along their respective lengths, cross pins extending through selected registering holes in said tubular legs and leg extensions for securing same together in one of a plurality of positions of coarse vertical adjustment as determined by the spacing of said holes, and screw means on the relatively outer ends of said leg extensions for effecting a fine adjustment in the vertical length of said leg members; and a beam-form hanger means extending in offset relation from at least one said

leg member and including cross-bolt securing means extending into one of the aforesaid holes of said leg member for securing said hanger means thereto at an elevation approximating that of the desired level of the beam-form and incorporating means for effecting a finer adjustment of its elevation; the construction and arrangement being such as to insure exact vertical positioning, both individually and with respect to one another, of a beam form supported on said hanger means and a slab form supported on said end frame through said leg members.

2. The combination substantially as set forth in claim 1, wherein said beam hanger means comprises a beam-form supporting bracket, a clamp member adapted to be secured to its leg member by said cross-bolt means, and means for securing the supporting bracket to the clamp member in one of a plurality of closely spaced vertical elevations with respect thereto.

3. The combination substantially as set forth in claim 1, wherein said beam hanger means comprises a beam-form supporting bracket, a clamp member adapted to be secured to its leg member by said cross-pin means, said clamp member including provision for securing itself to either the side or the front of said leg member.

4. The combination substantially as set forth in claim 1, whererin said tubular leg members each carries means

operable externally of but which extends into the bore thereof in position to engage with the portion of a leg extension telescoped in said bore, thereby to stabilize said leg member and leg extension against relative vertical motion.
